J. BAKKEN,
PIE PLATE ATTACHMENT,
APPLICATION FILED DEC. 16, 1921.

Patented June 20, 1922.

FIG. 1.

FIG. 2.

FIG. 3.

Inventor
Julia Bakken
by Herbert W. Jenner
Attorney.

UNITED STATES PATENT OFFICE.

JULIA BAKKEN, OF NORTHWOOD, NORTH DAKOTA.

PIE-PLATE ATTACHMENT.

1,420,466.

Specification of Letters Patent. Patented June 20, 1922.

Application filed December 16, 1921. Serial No. 522,813.

To all whom it may concern:

Be it known that I, JULIA BAKKEN, a citizen of the United States, residing at Northwood, in the county of Grand Forks and 5 State of North Dakota, have invented certain new and useful Improvements in Pie-Plate Attachments, of which the following is a specification.

This invention relates to attachments for 10 the plates in which pies are baked; and it consists in the novel construction and combination of the parts hereinafter fully described and claimed.

In the drawings, Figure 1 is a side view 15 of a pie plate provided with an attachment according to this invention. Fig. 2 is a plan view of the same. Fig. 3 is a side view of a portion of the attachment showing the corrugated flange.

20 The pie plate 4 is of any approved form, and it has a flange or rim 5 on which the outer portion 6 of the crust of the pie rests, and which also supports the corresponding portion 7 of the upper crust, when the pie 25 has an upper crust. In order to prevent juice from escaping out of the pie while being baked, and also to support and protect the pie after being baked, an attachment 8 is provided. This attachment is in the form 30 of a ring having a flange 9 at its lower part, similar to the flange 5 of the pie plate. The ring-shaped attachment projects upwardly from its flange 9, and it has a series of lugs 10 at its top. Four lugs are shown, but three 35 lugs, or more than four lugs can be provided.

The flange 9 is preferably corrugated in an ornamental manner to stiffen it, and also to ornament the pie in the usual manner, but it may be plain if desired.

40 Clamps 12 are pivoted to the flange 9, and project below the flange of the pie plate. These clamps may be of different widths, and the smaller clamps are used when the pie has no upper crust, and when there is 45 less thickness of crust between the flanges.

The flange 9 has a downwardly project-

ing cutting edge 14 at its periphery which engages with the rim of the pie plate.

The pie is formed in the pie plate in the usual manner, and the attachment is then 50 clamped over it, as shown in Fig. 1. The corrugated flange of the attachment ornaments the pie crust when pressed upon it. The pie is then baked, and the attachment prevents juice from leaking out around the 55 edge of the pie. When the pie is baked, it is taken off and turned over, and the lugs of the attachment form legs to support it on a shelf while it is cooling.

The attachment also permits a number of 60 pies to be packed together one above another, as it holds the pies apart, and protects them from injury. The top of the attachment is preferably open, and when no upper crust is used, the filling of the pie can be 65 placed in it after the attachment has been clamped to the pie plate.

The lower edge of the attachment cuts the 70 pie crust that extends outside the pie plate without the use of a knife.

What I claim is:

1. An attachment for a pie plate, comprising an annular member provided with a peripheral flange having a downwardly projecting cutting edge, said member having 75 also upwardly projecting lugs adapted to support it when inverted, and having also means for attaching it to a pie plate.

2. The combination, with a pie plate provided with a flange, of an annular attachment provided with a similar flange and having upwardly projecting lugs adapted to support the pie plate when inverted, and means for securing the two flanges together.

3. An attachment for a pie plate, comprising an annular member provided with a peripheral flange and upwardly projecting lugs adapted to support it when inverted, said attachment having also means for attaching it to a pie plate.

In testimony whereof I affix my signature.

JULIA BAKKEN.
